CLAIM

The ornamental design for a retainer accessory for garment hangers, as shown and described.

DESCRIPTION

FIG. 1 is a front elevational view of the retainer accessory for garment hangers showing my new design; FIG. 2 is a side elevational view taken from the right of FIG. 1;

FIG. 3 is a front elevational view in the retaining position, the hanger being shown in broken lines for illustrative purposes only;

FIG. 4 is a rear elevational view of FIG. 3 in the open position.

FIG. 1

FIG. 3
